UNITED STATES PATENT OFFICE

163,525

AUTOMOBILE BUMPER GUARD

George A. Lasko, Toledo, Ohio, assignor to
Chrysler Corporation, Highland Park, Mich.,
a corporation of Delaware

Application April 21, 1950, Serial No. 9,410

Term of patent 7 years

(Cl. D14—6)

To all whom it may concern:

Be it known that I, George A. Lasko, a citizen of the United States, residing in the city of Toledo, county of Lucas, and State of Ohio, have invented a new, original, and ornamental Design for an Automobile Bumper Guard, of which the following is a specification, reference being had to the accompanying drawing, forming part thereof, in which:

Fig. 1 is a front elevational view of an automobile bumper guard showing my new design;

Fig. 2 is a top plan view thereof;

Fig. 3 is a side elevational view thereof; and

Fig. 4 is an elevational view showing the side opposite to Fig. 3.

I claim:

The ornamental design for an automobile bumper guard, substantially as shown.

GEORGE A. LASKO.
